(57) **CLAIM**

The ornamental design for a rotor for a medical device, as shown and described.

DESCRIPTION

FIG. 1 is a bottom, front, left side perspective view of a rotor for a medical device according to a first embodiment of our new design;

FIG. 2 is a top, rear, left side perspective view thereof;

FIG. 3 is a bottom plan view thereof;

FIG. 4 is a top plan view thereof;

FIG. 5 is a left side elevation view thereof;

FIG. 6 is a right side elevation view thereof;

FIG. 7 is a front elevation view thereof;

FIG. 8 is a bottom elevation view thereof;

FIG. 9 is a bottom, front, left side perspective view of a second embodiment thereof;

FIG. 10 is a top, rear, left side perspective view of FIG. 9;

FIG. 11 is a bottom plan view of FIG. 9;

FIG. 12 is a top plan view of FIG. 9;

FIG. 13 is a left side elevation view of FIG. 9;

FIG. 14 is a right side elevation view of FIG. 9;

FIG. 15 is a front elevation view of FIG. 9;

FIG. 16 is a bottom elevation view of FIG. 9;

FIG. 17 is a bottom, front, left side perspective view of a third embodiment thereof;

FIG. 18 is a top, rear, left side perspective view of FIG. 17;

FIG. 19 is a bottom plan view of FIG. 17;

FIG. 20 is a top plan view of FIG. 17;

FIG. 21 is a left side elevation view of FIG. 17;

FIG. 22 is a right side elevation view of FIG. 17;

FIG. 23 is a front elevation view of FIG. 17;

FIG. 24 is a bottom elevation view of FIG. 17;

FIG. 25 is a bottom, front, left side perspective view of a fourth embodiment thereof;

FIG. 26 is a top, rear, left side perspective view of FIG. 25;

FIG. 27 is a bottom plan view of FIG. 25;

FIG. 28 is a top plan view of FIG. 25;

(Continued)

FIG. 29 is a left side elevation view of FIG. 25; FIG. 30 is a right side elevation view of FIG. 25; FIG. 31 is a front elevation view of FIG. 25; and, FIG. 32 is a bottom elevation view of FIG. 25. The dot-dash broken lines represent boundaries of the claimed design and form no part thereof. All other broken lines illustrate portions of the rotor for a medical device that form no part of the claimed design. The oblique shade lines in FIGS. 9-16 and 25-32 represent transparent surfaces.
